UNITED STATES PATENT OFFICE.

MARY C. GERARD, OF NORFOLK, VIRGINIA.

SHOE-HEATER.

SPECIFICATION forming part of Letters Patent No. 728,703, dated May 19, 1903.

Application filed July 31, 1902. Serial No. 117,742. (No model.)

To all whom it may concern:

Be it known that I, MARY C. GERARD, a citizen of the United States, residing at Norfolk, in the county of Norfolk, State of Virginia, have invented certain new and useful Improvements in Shoe-Heaters; and I do hereby declare the following to be a full, clear, and exact description of the invention, such as will enable others skilled in the art to which it appertains to make and use the same.

This invention relates to shoes, and more particularly to means for heating shoes, the object of the invention being to provide a shoe that may be worn by a person exposed to low temperatures and which will act to warm the foot without requiring it to be exercised to induce circulation.

A further object of the invention is to provide a construction in which a cheap and convenient heating medium may be employed and in which the ashes will be held until it is desired to empty them.

Other objects and advantages of the invention will be understood from the following description.

In the drawings forming a portion of this specification, and in which like numerals of reference indicate similar parts in both views, Figure 1 is a perspective view showing the shoe embodying the present invention. Fig. 2 is a vertical section taken longitudinally through the shoe.

Referring now to the drawings, there is shown a shoe comprising the upper 5 and insole 6, having the usual form and assembled in the usual manner, the upper and insole being made of whatever material or materials may be deemed most advisable to suit the conditions of use of the shoe. The sole 35 of the shoe comprises an upper metal plate 7 and a lower metal plate 8, which is spaced therefrom, and which plates are connected by the wall 9, the plates and wall being soldered with the wall against the upper face of the lower plate 8 and against the edge of the upper plate 7. The bottom plate 8 beyond the wall is turned upwardly to form the bead 10, between which and the wall 9 is engaged the asbestos strip 11, having an exterior facing 40 of leather. At the toe of the shoe is an opening 13, provided with a sliding door 14, the lower edge of which engages behind the

bead 10, while the upper edge is bent rearwardly and then downwardly and under the laterally-turned portion 15 of the upper edge 55 of the wall 9, that projects above the upper plate 7, so that the closure may be slid into and out of position over the opening. This closure has perforations 16 therethrough to permit of a draft. Upon the upper face of 60 the laterally-extending portion of the plate 7 is a layer 17 of asbestos and a layer 18 of leather, so that the exterior of the sole has a leather covering which gives it very much the appearance of the ordinary leather sole. 65 Through the wall 9, adjacent to the upper edge thereof, are perforations 19, which are continued through the asbestos and leather coverings and permit access of air to the interior of the sole to support combustion of 70 the punk 20, which is employed as a fuel. To prevent the ashes of the punk from blowing out through the perforations, foraminous coverings 21 are secured against the inner face of the wall over the perforations or openings, this material being of coarse cloth or any other style of screening. 75

To facilitate the draft through the shoe to insure proper combustion, a flat pipe 22 may be provided, leading from the upper portion 80 of the wall 9 at the rear of the heel upwardly and against the counter of the shoe, this pipe having a covering of leather or suitable enamel to render it inconspicuous.

In practice when the shoe is to be heated 85 the slide is drawn as shown in Fig. 1 and one end of the piece of punk is lighted and passed into the sole, after which the slide is moved to closed position. The combustion of the punk is very slow, so that it lasts a 90 long while and does not raise the temperature of the shoe above blood heat, there being enough air permitted to enter through the perforations in the sole and in the slide to support combustion. When the punk is consumed, 95 the ashes may be emptied from the shoe-sole and another piece of punk inserted, it being understood that if the heat is to be increased more than one piece of punk may be lighted or a single piece may be lighted at 100 both ends.

It will be understood that in practice modifications of the specific construction shown may be made and that any suitable materials

and proportions may be used for the various parts without departing from the spirit of the invention.

What is claimed is—

- 5 1. A shoe having a hollow sole comprising upper and lower spaced plates having a connecting-wall at their edges provided with ventilating-openings, said connecting-wall having an opening therethrough to permit of insertion of fuel, the edge of the upper spaced plate being turned upwardly, backwardly and downwardly above the opening to form a cylindrical bead and the lower spaced plate being turned upwardly below the opening, 15 the edge of the plate lying in a plane with the bottom of the opening and spaced slightly therefrom and forwardly of the connecting-wall, a cover for the opening having a semi-cylindrical bead at its upper edge for engagement over the bead upon the upper spaced plate, the lower edge of the cover ly-

ing in the space between the portion of the connecting-wall below the opening and the upwardly-turned portion of the lower spaced plate and a flue leading from the rear of the hollow sole to facilitate combustion of the fuel.

2. In a shoe the combination with a hollow sole having upper and lower spaced plates having a connecting-wall at their edges and 30 provided with ventilating-openings and a second opening to permit of the insertion of fuel, of a closure for the second opening and a flue connected with the rear of the hollow sole to facilitate combustion of the fuel.

In testimony whereof I affix my signature in presence of two witnesses:

MARY C. GERARD.
